HYDRAULIC TENSIONING RAM

Manfred E. A. Wyder, City of Industry, Calif., assignor
to Swiss-Aire Instruments, Inc., City of Industry, Calif.

Filed June 16, 1975, Ser. No. 587,108

Term of patent 14 years

Int. Cl. D15—99

U.S. Cl. D55—1 G

FIG. 1 is a left, front, perspective view of an elec-
ing ram showing my new design;

FIG. 2 is a bottom plan view;

FIG. 3 is an end elevational view of the end to the
left in FIG. 1;

FIG. 4 is an end elevational view of the end to the
right in FIG. 1; and

FIG. 5 is a side elevational view of the side not seen
in FIG. 1.

I claim:

The ornamental design for a hydraulic tensioning ram,
substantially as shown and described.
